UNITED STATES PATENT OFFICE.

JOHN B. WALKER, OF BIRMINGHAM, ALABAMA.

FLASK FOR INGOT-MOLDS.

1,221,117.

Specification of Letters Patent. Patented Apr. 3, 1917.

Application filed December 13, 1916. Serial No. 136,642.

To all whom it may concern:

Be it known that I, JOHN B. WALKER, a citizen of the United States of America, residing at Birmingham, in the county of Jefferson and State of Alabama, have invented 5 certain new and useful Improvements in Flasks for Ingot-Molds, of which the following is a specification.

My invention relates to a flask which is 10 especially though not exclusively adapted for use in the molding of ingot molds and like large tubular or hollow bodies.

The object of my invention is to simplify 15 the handling of the flask and the stripping of the casting therefrom, and to this end the flask, in its preferred embodiment, is split vertically and has its sections hinged at the top and provided with bottom fastenings which are detachable or removable. I provide 20 the flask with what I term "opening" lugs disposed in a plane at right angles to the plane of parting between the flask sections and arranged so that when engaged by the hoist tackle the latter will exert through 25 them a pull on the flask sections that will swing them apart on their hinges and open up the bottom of the flask. In order to facilitate the application of the bottom fastening, I provide each section of the flask with 30 a pair of what I term "closing" lugs so arranged that when the hoist tackle is passed over these four lugs it will draw the flask sections together in position to receive the fastenings. With this arrangement of 35 parts, by shifting the point of connection for the lifting tackle, the flask can be opened or closed and transported at will and I am enabled to eliminate the expensive labor charges that are now incurred in connection 40 with the stripping, assembling and handling of the flask, and to do the work with a minimum of time and trouble, thus materially reducing the manufacturing cost of castings made with my apparatus.

45 As illustrative of what I consider the preferred embodiment of my invention, but without intention to limit myself to the details disclosed, reference is made to the accompanying drawings which form a part of 50 this specification, and in which:

Figure 1 shows the flask in closed position with the crane loop applied to the "closing" lugs.

Fig. 2 is a similar view showing the crane loop applied to the "opening" lugs, the flask 55 being shown in open or stripping position.

Similar reference numerals refer to similar parts throughout the drawings.

I have illustrated my invention as applied to a flask for the manufacture of ingot molds 60 and I have divided such well known type of flask on a vertical plane into half sections 1 and 2. The section 1 is enlarged at one side to receive the gate for pouring the mold and the plane of parting between the sections 65 is arranged to pass midway through the oppositely disposed lifting lugs of the ingot mold, the flask being enlarged by offsets 5 to provide clearance for the lifting lugs as the flask is stripped vertically off the 70 mold. These sections 1 and 2 are provided at their upper ends with perforated lugs 3, and a pivot bolt 4 is passed through each pair of lapping lugs, thus serving to hingedly connect the sections 1 and 2 at their 75 upper meeting edges. I provide what I term pairs of "closing" lugs on each side of the flask, each pair comprising a lug on both sections, disposed close to their meeting edges and slightly above the middle of the 80 flask. The lugs of each pair are juxtaposed so that the chain or rope loop 15 of the hoist rigging can conveniently be passed over both at the same time, as seen in Fig. 1. Each flask section is also provided with one "opening" lug 7, which lugs are preferably disposed 85 above the flask center and lie diametrically opposite each other in a vertical plane at right angles to the plane of parting between the flask sections. On each side of the flask 90 near the lower ends of the offsets 5 I provide a pair of shoulders 8 which have countersunk notches in their upper edges to receive a U-shaped clamp 9 which drops into the notches and embraces the outwardly facing 95 sides of the shoulders so as to clamp and hold the flask sections together. As will be noted in Fig. 1, the inner edges of the side legs of the clamp are slightly tapering so that when the clamps are driven down a tight joint between the flask sections will be obtained. The shoulders 8 merge into lugs 10 which extend to the lower edge of the flask sections and are provided each with a transverse hole 11, the holes in adjacent lugs registering 100 and being adapted to receive a bolt 12 having

an enlarged head on one end and having a nut 13 on its other end, the nut being screwed only far enough to serve, in conjunction with the bolt head, to limit the opening movement of the lower ends of the flask sections.

In operation, when the ingot mold is cast in the flask, the sections thereof are clamped together and the mold and contained casting are transported to the point where the stripping operation is to take place. In conducting this operation, the first step is to knock off the clamps 9 after which the crane loop 15 is passed over the opening lugs 7, whereupon on hoisting the flask the pull of the loop

10 ends working over the top edge of the flask to the lugs 7, as seen in Fig. 2, will positively open out the bottom of the flask to the limit permitted by the bolts 12, which is sufficient to permit the casting to drop freely therefrom. After this takes place, by engaging the crane loop 15 over the pairs of lugs 6, the loop as it lifts the flask, will draw the lugs 6 of each pair together and close the flask so as to permit the fastening clamps 9 to be replaced in position. It will be seen that all manipulation of the flask requiring power can be done by the crane and I thus reduce to a minimum the labor for handling and stripping the flask.

20 30 It will be understood that the manner in which I have illustrated a flask is exemplary merely, and that any type of flask may be adapted to my invention and parted in as many sections as good practice may require 35 in each particular case.

It will be noted that the clamp and limit means are simple and rugged, and moreover, are of such character that the sand and hot metal falling on them will not hang and 40 interfere with their operation. The lugs 8 and clamp 9 are peculiarly adapted for use on a jarring table, it being noted that the clamp is so disposed that it will tighten during the jarring operation and the shoulders 45 at the outer ends of the lugs form pockets which receive and hold the clamp between them and the flask to prevent any outward displacement thereof. The limit means also is of such character that the jarring operation 50 will not affect it.

One of the most important advantages resulting from the operation of my flask is that it opens up in such manner as to leave the mold sand adhering to the casting and 55 this causes the latter to anneal as the result of the slow and gradual manner in which it cools. In operation, the castings as stripped from the flask are set aside and allowed to cool at least twelve hours before they are 60 cleaned, and as a result the sand will strip freely from the casting.

When I refer to the sections as hinged, I mean to include any means for connecting the upper ends of the sections so as to hold 65 them against parting while the flask is on

the jarring table and which will permit the lower ends of the flask to open out or expand.

Having thus described my invention, what I claim as new and desire to secure by Letters Patent, is:

1. A mold flask formed in vertical sections which are hingedly connected so that the sections can swing apart at a lower end of the flask, lugs near the lower ends of the flask sections, clamps engaging the tops of the lugs and adapted to hold the free ends of the flask sections together in assembled position, and lugs on the sections adapted to engage hoisting tackle and disposed in position thereon to adapt the weight of the flask, when suspended by said lugs, to swing the sections apart when free of their holding means and expand the flask, substantially as described.

2. A mold flask formed in vertical sections which are hingedly connected so that the sections can swing apart at a lower end of the flask, detachable clamp means to hold the free ends of the flask sections together in assembled position, lugs on the sections adapted to engage hoisting tackle and disposed in position thereon to cause the weight of the flask, when suspended by said lugs, to tend to swing the sections apart and expand the flask, and stop means carried by the flask sections to limit their outward swing.

3. A flask for molds parted vertically to form sections hingedly connected near their upper ends, means to fasten the free lower ends of the flask sections together in assembled position, and pairs of juxtaposed lugs adapted to engage hoisting tackle, each pair comprising lugs on adjacent flask sections, substantially as described.

4. A flask for molds divided vertically into half sections, means to hingedly connect said sections so that their lower ends can swing apart, releasable means to fasten the sections together at their lower ends, and "lifting" lugs disposed near the middle and near each side edge of the upper portion of each flask section, substantially as and for the purposes described.

5. An ingot mold flask divided vertically into half sections which are hinged together at their upper ends and adapted to swing apart at their lower ends, means to limit the opening movement of the flask sections, and "lifting" lugs on each flask section adapted for engagement with hoist tackle, each section having a lug near each side edge and a lug substantially midway between its side lugs, the adjacent side lugs of the flask sections forming a juxtaposed pair adapted to be received in the bight of the hoist tackle.

6. An ingot mold flask divided vertically into half sections on a plane in line with the lugs on the ingot mold to be cast therein, the

flask being enlarged opposite the position for the mold lugs to permit the latter, when being stripped from the flask, to pass downwardly through the flask, means to pivotally connect the flask sections together at their upper ends, releasable means to hold the flask sections together at their lower ends, and "lifting" lugs on the flask arranged to coöperate with lifting tackle in

- 10 opening and closing the flask sections, substantially as described.

7. An ingot mold flask divided vertically into half sections which are hinged at their upper ends, lugs near each lower side edge of 15 said flask sections, said lugs forming juxtaposed pairs on each side of the flask and having alining notches in their upper edges, clamps adapted to seat in said notches and embrace each a pair of said lugs, each flask 20 section having in its upper portion a flask "closing" lug near each edge, a flask "opening" lug disposed substantially midway between the "closing" lugs of its respective flask section, substantially as described.

25 8. In an ingot molding flask having on each side opposite the mold lugs an offset extending to the bottom edge of the flask to provide for stripping the mold lugs there-through, the flask being divided into half 30 sections on a vertical plane intersecting said offsets, horizontal alining pivot pins to connect the flask sections at the top, clamp means to connect the flask sections at the bottom, co-acting means on the flask sections 35 to limit their bottom opening movement, a pair of "lifting" lugs on each side of the flask, each pair comprising a lug on each flask section, and a flask "opening" lug on each section, said opening lugs being disposed in a vertical plane substantially at right angles to the plane of parting between the flask sections.

40 9. An ingot mold flask adapted for use on a jarring table and formed by hinged vertical sections, and releasable fastening means for the lower ends of the flask adapted to be tightened by the jarring operation.

45 10. An ingot mold flask adapted for use on a jarring table and formed by hinged vertical sections, releasable fastening means for the lower ends of the flask adapted to

be tightened by the jarring operation, and lugs on the flask disposed to co-act with hoisting tackle to expand the flask when 55 said fastening means is released.

11. An ingot mold flask adapted for use on a jarring table and formed by vertical sections hingedly connected at their upper ends, lugs near the lower ends of the flask 60 sections having upwardly facing notches, inverted U-shaped clamps adapted to fit in said notches and embrace adjacent pairs of lugs to hold the sections in assembled relationship, and lifting lugs adapted to co- 65 operate with hoisting tackle in opening the lower ends of the flask sections when released, substantially as described.

12. An ingot mold flask divided vertically into sections, means connecting the upper 7 ends of the sections together in a manner to permit their lower ends to swing apart, means to limit the opening movement of said sections, and "lifting" lugs on the flask arranged to coöperate with lifting tackle in 75 opening and closing the flask sections, substantially as described.

13. An ingot mold flask split vertically into sections hinged together at their upper corner edges, demountable fastenings one 80 disposed on each side of the flask near the lower ends of the section edges and adapted to secure the flask sections together, means to limit the expanding movements of the flask sections when the fastenings are attached and, a lifting lug on each section 85 adapted to coact with hoisting tackle to expand the flask sections when released.

14. An ingot mold flask split vertically into sections hingedly connected at their upper ends, means to secure the lower ends of the sections together, comprising lugs on the sections and removable clamps adapted to engage the lugs, means to limit the opening movements of the flask comprising a member passing freely through each pair of lugs and having stop means on its ends, and lifting lugs adapted to coöperate with the hoist tackle in opening the flask sections when released, substantially as described. 95

In testimony whereof I affix my signature.
JOHN B. WALKER.
